Primary Examiner — Mehri F Bajoul(74) *Attorney, Agent, or Firm* — Gugliotta & Gugliotta LPA(57) **CLAIM**

The ornamental design for face plate set for cornhole game as shown and described.

DESCRIPTION

FIG. 1 is a perspective view of a face plate set for cornhole game showing my new design with environmental structure shown in broken lines;

FIG. 2 is an exploded perspective view thereof;

FIG. 3 is a top plan view thereof;

FIG. 4 is a bottom plan view thereof;

FIG. 5 is a right elevational view thereof;

FIG. 6 is a left elevational view thereof;

FIG. 7 is a front elevational view thereof; and,

FIG. 8 is a rear elevational view thereof.

The broken lines in the drawings depict portions of the face plate set for cornhole game that form no part of the claimed design. The broken line cornhole game in FIGS. 1 and 2 illustrates environmental structure and forms no part of the claimed design.
